UNITED STATES PATENT OFFICE.

JOHN KESTLY, OF PORTLAND, OREGON.

MIXING DEVICE.

Application filed May 28, 1924, Serial No. 716,446.

To all whom it may concern:

Be it known that I, JOHN KESTLY, a citizen of the United States, residing at Portland, in the county of Multnomah and State of Oregon, have invented certain new and useful Improvements in a Mixing Device, of which the following is a specification.

This invention relates to an improved fuel mixing device especially designed for use in connection with internal combustion engines, although the device may well be employed in various other situations, and seeks, among other objects, to provide a device which will function to effectually mix the fuel gas and air of the fuel supply of an engine or the like so that a thoroughly efficient combustion will be had.

The invention seeks, as a further object, to provide a device which may be interposed between the engine carbureter and the intake manifold of the engine for mixing the fuel in its passage from the carbureter to the engine so that the ultimate carbureted product will not only readily ignite but will burn completely, thereby not only effecting an increase in power but also effecting a reduction in the formation of carbon in the engine cylinders.

Other and incidental objects will appear hereinafter.

In the drawings:

Figure 1 is a view partly in elevation and partly in section, showing my improved device interposed between a conventional carbureter and engine intake manifold,

Figure 2 is a detail sectional view through the device,

Figure 3 is a detail elevation showing the body plate of the device, and

Figure 4 is a fragmentary side elevation showing the use of the device in conjunction with a heating boiler.

In carrying the invention into effect, I employ a body plate 10 which, as shown in Figure 1 of the drawings, is shaped to register with the confronting flanges 11 of a carbureter 12 and engine intake manifold 13, providing a gasket between the flanges. The carbureter and manifold are, of course, conventionally illustrated and inserted through the flanges 11 and through the plate 10 are the usual bolts 14 securing the parts together. Formed in the plate 10 centrally thereof is an opening 15 in which is disposed a spider 16 and pressed through the

hub of the spider to extend axially of said opening is a shaft 17 frictionally locked against rotation. Mounted upon the end portions of the shaft at opposite sides of the plate 10 is a pair of mixing fans. These 60 fans include fan discs 18 which may be struck from suitable sheet metal and are provided with a plurality of radial blades, the discs being identical with the exception that the blades of the discs are, as shown 65 in Figure 1, twisted in opposite directions. Mounting the discs are hubs 19 which are journaled upon the shaft 17 and are provided at corresponding ends thereof with annular flanges 20 to confront the hubs of the spider 70 16. The discs 18 are apertured centrally to fit over the hubs 19 abutting the flanges 20 and surrounding the hubs to seat against said discs are clamping rings 21. After the discs and clamping rings have been applied, the 75 hubs are then formed at their outer ends with flanges 22 to bear against the rings 21 for clamping the discs between said rings and the flanges 20. Thus, the discs and hubs will be secured to turn in unison. Fitting 80 over the ends of the shaft 17 are retaining washers 23 for the fans and inserted through the shaft are pins 24 removably securing the parts in assembled relation.

As will now be seen in view of the foregoing description, when the engine is running and fuel vapors are drawn from the carbureter 12 into the manifold 13, the fans of the device will be caused to rotate upon the shaft 17 and since the fan blades are 85 oppositely twisted, the fans will turn in opposite directions. Thus, the fans will cut through the fuel vapors to mix and commingle the component parts of the fuel charge with the result that a homogeneous fuel supply will be delivered to the engine. More 90 complete combustion than is now obtained will thus be realized, with a corresponding increase in the efficiency of the engine as well as a corresponding decrease in the formation of carbon in the engine cylinders. As will be observed, the fans are quite closely spaced so that any liquid particles thrown from the blades of either fan toward the other will strike the blades of the latter fan when the impact will, of course, serve to 100 break up the particles to be taken up by the vaporous currents flowing through the fans. Furthermore, the fan nearest the carbureter will, as will be seen, tend to impart a swirl- 105 110 115

ing motion to the fuel vapors but the swirling currents thus started will be opposed by the movement of the fan furthest removed from the carbureter. Thus, the latter fan 5 will cut through the currents set up by the former fan in a direction opposite to the flow of said currents, with the result that the fan furthest removed from the carbureter will exert a rubbing action on the currents 10 impacted thereagainst for removing practically all unvaporized particles from the fuel mixture. I accordingly provide a particularly effective device for the purpose set forth and, as will be seen, a device which 15 may be readily installed.

In Figure 4 of the drawings, I have 20 illustrated my improved device in connection with a conventional boiler 25. Leading to an approved liquid fuel burner within 25 the boiler is a pipe 26 to which is connected a supply pipe 27 and interposed between said pipes is the present device, indicated as a whole at 28, bolts 29 being employed for connecting the pipes as well as securing the device in position. Thus, as the liquid fuel 25 is forced under air pressure from the pipe

27 to the burner within the boiler, the fuel will be broken up into particles by the fans of the device so that better combustion will take place.

Having thus described the invention, what I claim is:

A mixing device including a body plate having an opening and provided with a spider to extend across said opening, a shaft extending through the spider axially of the opening, hubs journaled upon the shaft at opposite sides of the spider and provided with flanges to confront the spider, fan discs fitting over the hubs to abut said flanges 35 and provided with oppositely twisted blades, and rings surrounding the hubs to confront the discs, the hubs being formed at their outer ends with flanges bearing against said rings for clamping the discs between the 40 rings and said first mentioned flanges whereby the hubs and discs will be secured to turn in unison forming oppositely rotating fans at opposite sides of said body plate.

In testimony whereof I affix my signature.

JOHN KESTLY, [L. S.]
